EMBROIDERED FABRIC

Herman Krieger, New York, N. Y., assignor to Kaufman & Krieger, Inc., New York, N. Y.

Application October 29, 1951, Serial No. 17,149

Term of patent 3½ years

(Cl. D92—1)

To all whom it may concern:

Be it known that I, Herman Krieger, a citizen of the United States of America, residing in New York city, county of New York, and State of New York, have invented a new, original, and ornamental Design for an Embroidered Fabric, of which the following is a specification, reference being had to the accompanying drawing, forming part thereof, wherein, the figure on the drawing is a plan view of a piece of embroidered fabric showing my new design, which is repeated lengthwise along the fabric as shown.

I claim:

The ornamental design for an embroidered fabric, substantially as shown and described.

HERMAN KRIEGER.
